UNITED STATES PATENT OFFICE.

ARTHUR W. JONES, OF SCHENECTADY, NEW YORK, ASSIGNOR TO GENERAL ELECTRIC COMPANY, A CORPORATION OF NEW YORK.

SELECTIVE SIGNALING SYSTEM.

No. 921,116.

Specification of Letters Patent.

Patented May 11, 1909.

Application filed May 8, 1906. Serial No. 315,751.

To all whom it may concern:

Be it known that I, ARTHUR W. JONES, a citizen of the United States, residing at Schenectady, county of Schenectady, State 5 of New York, have invented certain new and useful Improvements in Selective Signaling Systems, of which the following is a specification.

My invention relates to selective signaling systems of the type in which a signal at any one of a plurality of stations may be selectively actuated from a single point, and its object is to provide means for actuating all the signals automatically upon a breakdown 15 of the apparatus. Such systems are ordinarily arranged with electrically-operated step-by-step devices at the several stations, so that by sending a predetermined number of impulses over a conductor from the central 20 station all the devices will be moved a predetermined distance; this movement putting one of the signals into condition for operation from the central station.

My invention consists in the combination 25 in such a system of a wire connecting all the stations and normally carrying current, devices at the several stations arranged to be moved step-by-step by impulses of increased current-strength in the wire and means for 30 actuating the signals upon a failure of current in that wire. In this manner, while the signals are selectively controllable from the central station, they are all automatically put at stop position upon a failure of the signal apparatus, so that accidents due to such failure 35 are prevented.

My invention further consists in employing the same wire which has been used heretofore 40 for conveying the impulses to the selective devices as the wire which normally carries current. Thus, I am enabled to obtain the desired results without employing an additional wire between stations. For this purpose I arrange the electrical operating means 45 for the selective devices so that they do not respond to the current normally in the wire, but are actuated by sending impulses of increased current strength over the wire.

My invention further consists in providing 50 automatic means for connecting the wire above-mentioned to a second source of current in case the first source should fail.

My invention will best be understood by 55 reference to the accompanying drawing, which shows diagrammatically a selective

signal system arranged in accordance with my invention.

In the drawing A represents the sending station and B one of the receiving stations, which may be one of a number of stops along 60 an electric railway, for instance. At each signal station there is provided a step-by-step device, such for instance, as the ratchet wheel C and the spring-actuated pawl D operated by the electro-magnet E.

F represents a toothed wheel which is adjustably secured to the ratchet wheel C and carries the arm g. This arm g carries a contact G, which, when the ratchet wheel has been moved a distance of three teeth at this 65 particular station, engages the stationary contact H.

I represents a signal counter-weighted to go to danger when released and normally held at clear position by the lock i and the 70 slow-acting locking magnet J.

K represents a magnet controlled by the switch contact G, normally deenergized, but adapted when its circuit is closed to overpower the locking magnet J, so as to release 75 the signal.

L¹, L² and L³ are line-wires connecting the sending-station with the several receiving stations. The lines L² and L³ normally carry current at comparatively low voltage, while 80 the line-wire L¹ is normally deenergized. At the sending-station is a source of current M, which is connected across the line-wires L² and L³ through the resistance N, the magnet 85 O and the switch P. The resistance N is so 90 designed with respect to the resistance of the several magnets connected to the line, that the voltage across the line-wires L² and L³ is comparatively low. For instance, if the generator M is arranged to give five hundred 95 volts, the resistance N might be arranged normally to consume four hundred volts in ohmic drop. The remaining hundred volts between line-wires L² and L³ is sufficient to 100 energize lock magnet J to sustain the lock i, but insufficient to energize magnet E to draw up the panel D against the tension of the spring. The magnet O, in series with the source M, controls a weighted switch Q 105 which, upon the deenergizing of magnet O, cuts the battery R into circuit with line-wires L² and L³. This battery may be arranged to give one hundred volts so that when cut into circuit on the failure of generator M, it will maintain the normal voltage on 110

the line-wires L^2 and L^3 until the generator M is again ready for service.

The selective switch device comprises a pivoted arm carrying a contact S, which is 5 adapted to engage successively the contacts 1, 2 and 3, etc., as the arm is rotated. It will be seen that when contact S is in engagement with any one of these contacts it shorts-circuits resistance N, so as to impress the full 10 voltage of the source M upon the line-wires L^2 and L^3 . In this manner a series of impulses of increased current-strength is sent over the line, so that the magnets E, which are designed not to respond to the low voltage 15 normally on the line, are actuated by the increased voltage, so as to move the ratchet wheel C as many teeth as the number of contacts 1, 2, 3, etc. successively engaged by contact S. If, for instance, the contact 20 G, which is differently arranged at the several receiving-stations, is so arranged at station B as to engage contact H when ratchet wheel C is moved a distance of three teeth, then when contact S has reached contact 3, 25 contact G will be in engagement with contact H at station B; at the other stations it will not have reached, or will have passed contact H. Now if, while contacts G and H are in engagement, the spring-actuated contact 30 T is pressed radially inward, so as to engage the contact strip U, a circuit will be closed from right-hand terminal of generator M through contacts T and U, to line-wire L^1 , thence through magnet K at station B and 35 contacts H and G, to line-wire L^2 , and to the left-hand terminal of the generator. Magnet K at station B is consequently energized, and as has been said heretofore, is so arranged 40 as to over-power lock magnet J and to cause latch I to drop and signal I to be moved to danger by the counter-weight. In this manner any signal of the system may be set at danger from the central station, so as to stop a car at any point on the road.

45 It will be understood that the conductor of a car, after being stopped by a signal at danger and communicating with the sending station by telephone, restores the signal to its clear position before proceeding. Consequently, no automatic devices for returning the signal are shown.

It will be seen that if the apparatus should at any time break down so as to deenergize the line-wires L^2 and L^3 , to render impossible 55 the control of the signals from the central station, all the slow-acting lock-magnets J would be deenergized so as to place all signals on the road at stop-position. In this way, possible accidents due to failure of apparatus 60 are prevented, but in order to prevent unnecessary interruption of traffic from such causes as the blowing of a circuit-breaker or other incidents of like nature which might temporarily cut off the line-wires from the 65 source of current, I utilize the battery R and

the automatic switch Q controlled by the magnet O to keep the signals at clear position until the generator M is again ready for use.

All the signals may be put at stop position, 70 when the generator M is being used, by opening the switch P, or when the battery R is being used, by opening the switch V.

I have not considered it necessary to indicate in the drawings or to describe any return signal device, such as is frequently employed 75 in systems of this character, because such devices are well known in the art, and any suitable form of device may be used. Furthermore, it will be understood that my invention is applicable to signal systems employing any well known type of selective device, and consequently I do not desire to limit myself to the particular construction and arrangement of parts here shown, but aim in 80 the appended claims to cover all modifications which are within the scope of my invention.

What I claim as new and desire to secure by Letters Patent of the United States, is,—

1. In a selective signaling system, a plurality of signal stations, a wire connecting said stations and normally carrying current, selective signal-controlling devices at the several stations, means at the several stations 90 for moving said devices step-by-step responsive to impulses of increased current-strength in said wire, and means for actuating all the signals upon a total failure of current in said wire.

2. In a selective signaling system, a plurality of signal stations, signal devices adapted when released to move automatically to stop position, a wire connecting said stations and normally carrying current, electro-magnets at the several stations connected to said wire and normally locking the signal devices at clear position, and electrically-actuated step-by-step devices adapted to unlock said signals selectively.

3. In a selective signaling system, a plurality of signal stations, signal devices adapted when released to move automatically to stop-position, a wire connecting said stations and normally carrying current, electro-magnets at the several stations connected to said wire and normally locking the signal devices at clear position, selective signal-controlling devices at the several stations, and electro-magnets connected to said wire adapted to move said selective devices step-by-step upon impulses of increased current strength in said wire.

4. In a selective signaling system, a plurality of signal stations, signal devices adapted when released to move automatically to stop-position, a wire connecting said stations and normally carrying current, electro-magnets at the several stations connected to said wire and normally locking the signal devices

at clear position, step-by-step devices at the several stations, actuating electro-magnets for said step-by-step devices connected to said wire and responsive to impulses of increased current therein, and means selectively controlled by said step-by-step devices for unlocking the several signals.

5. In a selective signaling system, a sending station, a plurality of receiving stations, signal devices at the receiving stations adapted to move to stop-position when released, a wire connecting said stations, means at the sending station for normally maintaining a voltage on said wire, electro-magnets at the receiving stations connected to said wire and normally locking said signal devices in clear position, and means whereby said devices may be selectively unlocked from the sending station.

10 6. In a selective signaling system, a sending station, a plurality of receiving stations, signal devices at the receiving stations adapted to move to stop position when released, a wire connecting said stations, means at the sending station for normally maintaining a voltage on said wire, electro-magnets at the receiving stations connected to said wire and normally locking said signal devices in clear position, means at the sending station for increasing the voltage on said wire at will, and selective signal-controlling means at the receiving stations connected to said wire and responsive to impulses of increased voltage.

15 7. In a selective signaling system, a plurality of signal stations, selective signal controlling devices at the several stations, electro-responsive means for moving said devices step-by-step, a wire connecting said stations, a source of current normally connected to said wire; means for actuating all the signals upon a failure of current in said wire, a second source of current, and means for automatically connecting said second source to said wire upon a failure of the first

20 45 8. In a selective signaling system, a plurality of signal stations, selective signal-con-

trolling devices at the several stations, electro-responsive means for moving said devices step-by-step, a wire connecting said stations, a source of current normally connected to said wire, means for actuating all the signals upon a failure of current in said wire, a second source of current, an electro-magnet in circuit with the first source, and means operative upon the deenergizing of said magnet for connecting the second source to said wire.

9. In a system of the character described, a plurality of track signals, normally energized electro-magnets adapted to lock said signals at safety position, selective signal switches adapted to release said signals, a single line circuit in which said magnets and switches are included, and a controller for setting said switches in operation, said switches being so adjusted relatively to each other that but one signal can be set by the controller at a given time.

10. In a system of the character described, a plurality of track signals, normally energized electro-magnets adapted to lock said signals at safety position, selective signal switches each comprising an electrically actuated step-by-step mechanism, a single line circuit in which said magnets and switches are included, and means for actuating the said mechanism of a given switch to effect the release of the corresponding signal.

11. In a system of the character described, the combination of a plurality of signals, normally energized electro-magnets adapted to hold said signals at safety position, selective signal switches comprising a ratchet wheel, a single line circuit in which said magnets and switches are included, and means to feed a given wheel a predetermined distance to effect the setting of the corresponding signal.

In witness whereof, I have hereunto set my hand this 7th day of May, 1906.

ARTHUR W. JONES.
